DIAMOND A. SNOOK, OF TAFT, CALIFORNIA, ASSIGNEE OF TWO-FIFTHS TO PERCY G. CUMMING, OF LONG BEACH, CALIFORNIA.

COMBINATION CRANE AND MOTOR STAND.

Application filed March 24, 1925. Serial No. 17,978.

This invention relates to garage equipment and it particularly concerns a device which is very useful for removing motor blocks from automobiles and holding same during repairing thereof.

At present, under ordinary conditions, it requires two or three men to remove a motor block from place. The motor block is usually set on horses or on a bench during the repairing thereof. Labor required for removing and installing the motor is quite expensive and repairing of the motor is encumbered by not having proper supporting means to hold it in desirable positions.

It is an object of my invention to provide a device by use of which one man can remove and install a motor or motor block.

It is another object of my invention to provide a device of this character by use of which one man can secure a motor block thereto so that it may be conveniently repaired. I provide my invention in the form of a base having a column extending therefrom. Carried by the column is a crane post which supports a crane. The column carries a motor supporting member. When using the device, the crane is attached to the motor block and is elevated from place. The motor support which has been removed from the column is then secured to the motor, after which the motor block is brought into proper position so that the motor support may be again secured to the column.

It is a further object of my invention to provide a device of the character mentioned in which the base thereof is designed so that it may be moved into the position where the crane will be held centrally of the motor of a vehicle. I accomplish this by providing a base of substantially triangular shape which has forked legs. These forked legs may extend around the wheels of the vehicle to allow proper positioning thereof.

It is also an object of my invention to provide a device of the character mentioned having a crane post which is swingable. This permits the crane to be swung into desired position for removing the motor block, and also allows it to be swung out of the way so that it will not interfere during repairing of the block.

A still further object of my invention is to provide a motor support which is adjustable. I provide an arrangement whereby the

support may be removed laterally or it may be revolved. The motor block attached thereto may be removed into any position convenient for the repairing thereof. This feature saves considerable time as it was previously necessary to reach under and around the motor to make various repairs, due to the fact that there were previously no practical means for holding it in a desired position.

It is a still further object of my invention to provide a means for locking the motor support in any position.

A further object of my invention is to provide a device of the character mentioned which is very sturdy in construction and may be cheaply produced. The device is produced essentially from pipes and tubing and flat plates which are all welded together. The parts are designed and reinforced so that the device is very rugged.

Other objects and the particular advantages of this invention will be made evident hereinafter.

Referring to the two sheets of drawings in which I illustrate my invention,

Fig. 1 is a perspective view showing the device of my invention.

Fig. 2 is a plan view of my invention.

Fig. 3 is an enlarged contracted sectional view taken through the column and crane post, substantially on the line 3-3 of Fig. 1 of my invention.

Fig. 4 is a section taken on the line 4-4 of Fig. 1. This view clearly shows the arrangement for holding the motor support of my invention and shows the arrangement for locking the same in desirable positions.

With particular reference to Fig. 1 of the drawings, my invention has a base 11 which is comprised of forked legs 12 which are brought together and extend substantially parallel as indicated at 13. The parallel ends 13 of the legs 12 are secured together by upper and lower plates 14 and 15 which are welded thereto, as indicated at 16. The base 11 is movably supported on casters 17, 18 and 19. The caster 17 is positioned at the ends of the portions 13 of the legs 12, and the casters 18 and 19 are positioned at the forked ends of the legs 12.

Extending upwardly from the base 11 is a tubular column 21. This column 21, as clearly shown in Fig. 2, extends between

the parallel portions 13 of the legs 12 and through openings 23 and 24 in the plates 14 and 15. The tubular column 21 is secured to the base by welding, as indicated at 26.

- Extending horizontally and radially through the tubular column 21, near the upper end thereof, is a mandrel tube 28 which is welded thereto, as indicated at 29. Extending through the mandrel tube 28 is a mandrel 30 of a motor support 31. A supporting plate 32 is secured to an end of the mandrel 30, as by welding 33. Threaded nuts 34 are welded or otherwise secured on opposite sides of an inner end of the mandrel tube 28. Threadably carried by these nuts 34 are lock pins 36 having cranks 37. By turning the cranks 37, the lock pins 36 may be rotated, causing the inner ends 38 thereof to engage the mandrel 30, thus securing it tightly in place.

Directly adjacent to the upper end of the tubular column 21 there is secured a collar 40 which is secured in place, preferably by welding 41. Extending around the upper end of the column 21 and resting on the collar 40 is a sleeve 43 of a tool tray 44. A set screw 45 is retained by the sleeve 43 for locking the tool tray 44 in any position.

A lower end 50 of a crane post 51 extends into the upper end of the tubular column 21, and the lower end thereof engages the portion of the mandrel tube 28 resting inside the column 21. This portion of the tube 28 serves as a stop for the crane post 51. As shown clearly in Fig. 1, the upper end 53 of the crane post 51 is curved. At the extreme upper end 54 of the post 51 there is secured an eye-bolt 55 which is adapted to support a chain-block 56, a hook 57 of the chain-block 56 extending through the eye-bolt 55.

For supporting the crane post 51 at the curved portion 53, I provide a web 59 which is secured in place by welding 60. At the lower part of the curved portion 53, there is an eye 62 with which a guy-bar 63 connects. The lower end of the guy-bar 63 is secured to the rear end 64 of the base 11 by means of a bolt 65. This guy-bar 63 is provided for the purpose of holding the crane post 51 in an upright position and to oppose strains which are placed thereon when a motor or block is carried by the chain-block 56.

In using my device, the lock pins 36 are loosened and the motor support 31 is removed from place. The device is then moved in position so that the crane 56 is positioned directly over the motor block to be removed from a vehicle. Due to the fact that the legs 12 are forked, as shown, they may be extended around the front wheels of the vehicle and will permit the proper positioning. The chain-block 56 is then secured to the motor or cylinder block and it is ele-

vated from place. The device is then moved away from the vehicle and the supporting plate 32 is secured to the side of the motor 70 by bolts 71, as shown in Fig. 1. I provide a number of different supporting plates 32, each of which is suitable for a different motor.

After the plate 32 has been secured to the motor 70, the motor 70 is lowered so that the mandrel 30 aligns with the mandrel tube 28. The mandrel 30 is then extended into the tube 31 after which the chain-block 56 is detached from the motor 70. The chain-block 56 is then unhooked from the eye-bolt 55 and the crane post 51 is swung to one side, as indicated by either of the dotted line positions 72 or 73. This moves the post so that it will not interfere with a workman repairing the motor 70.

From the drawings, it will be seen that the motor support 31 may be removed laterally, that is, the mandrel 30 may be slid in or out of the tube 28, and it may be moved rotationally as well. The motor support 31 may be locked in any position by tightening one or both of the lock screws 36. It is desirable to have a pair of lock screws 36 owing to the fact that sometimes the motor 70 is not balanced on the supporting member 31 and it is, therefore, necessary to have a very rigid securing. Two lock screws of this character provide this. By providing axial, as well as rotational, adjustability of the member 31, it is possible to extend the motor 70 into a variety of positions which will permit convenient access to any portions thereof, this greatly facilitating and expediting the repairing of the motor.

After the motor 70 has been completely overhauled, the crane post 51 is swung into the position shown in full lines in the drawing and the chain-block 56 is attached to the eye-bolt 55 and the motor 70 is secured to the hook on the travelling block of the chain-block. The lock screws 36 are then loosened and the supporting member 31 is freed from the mandrel 28 and detached from the motor or cylinder block 70. The device is then moved so that the motor is placed over its proper position and the chain-block is then operated to move the motor into its original position in the vehicle.

The tray 45 is preferably used for holding tools and, as previously mentioned, may be rotatably swung into any convenient position and secured thereto by tightening the set screw 45.

The device of my invention is very cheap to produce owing to the fact that it is made essentially from pipes, plates and bars which are welded together. There are no intricate parts to my device. It is very sturdy owing to the use of very rugged parts, and owing to the special construction and supporting

members. The guy-bar 63 entirely prevents any skewing of the crane post 51. The eye-bolt 55 at all times rests within the limits of the three casters 17, 18 and 19, and there is therefore no danger of the device tipping over.

From the description and drawings, it is obvious that the removing of a motor may be accomplished by one man when using my invention. This is a great saving over the present methods. At present it requires two or three men to remove a motor from place and even then, it is quite a task.

I claim as my invention:

1. In a device of the class described, the combination of: a base having forked legs; a column supported by said base; a crane post swingably carried by said column; a mandrel sleeve carried by said column; a mandrel supported in said sleeve; a supporting plate carried by said mandrel; and lock-bolts for securing said mandrel in said sleeve in any desired position.

2. In a device of the class described, the combination of: a base having forked legs; a column supported by said base; a crane post swingably carried by said column; a mandrel sleeve carried by said column; a mandrel slidably supported in said sleeve; a supporting plate carried by said mandrel; and lock-bolts for securing said mandrel in said sleeve in any desired position.

3. In a device of the class described, the combination of: a base having forked legs; a column supported by said base; a crane post swingably carried by said column; a mandrel sleeve carried by said column; a mandrel supported in said sleeve; a supporting plate carried by said mandrel; lock-bolts for securing said mandrel in said sleeve in any desired position; and a guy-bar extending between said crane post and said base.

4. In a device of the class described, the combination of: a base; a column carried by said base; a crane post carried by said column; a crane carried by said crane post; a mandrel sleeve carried by said column; a mandrel extending into said sleeve; a supporting plate carried by said mandrel; and

means for securing said mandrel in said sleeve in any desired position.

5. In a device of the class described, the combination of: a base having forked legs; a column carried by said base; a crane post 55 carried by said column; a mandrel extending into said sleeve; a supporting plate carried by said mandrel; and means for securing said mandrel in said sleeve in any de- 60 sired position.

6. In a device of the class described, the combination of: a base; a column carried by said base; a tray supported by said column; a crane post carried by said column; a mandrel sleeve carried by said column; a mandrel extending into said sleeve; a supporting plate carried by said mandrel; and means for securing said mandrel in said sleeve in any desired position. 70

7. In a device of the class described, the combination of: a base; a column carried by said base; a crane post carried by said column; a mandrel sleeve carried by said column; a mandrel extending into said sleeve; a supporting plate carried by said mandrel; and lock-bolts for securing said mandrel in said sleeve in any desired position. 75

8. In a device of the class described, the combination of: a base having forked legs; a column carried by said base; a crane post carried by said column; a mandrel sleeve carried by said column; a mandrel extending into said sleeve; a supporting plate carried by said mandrel; and lock-bolts for se- 80 curing said mandrel in said sleeve in any desired position. 85

9. In a device of the class described, the combination of: a base; a column carried by said base; a tray supported by said column; a crane post carried by said column; a mandrel sleeve carried by said column; a mandrel extending into said sleeve; a supporting plate carried by said mandrel; and lock-bolts for securing said mandrel in said 90 sleeve in any desired position. 95

In testimony whereof, I have hereunto set my hand at Taft, California, this 17 day of March, 1925.

DIAMOND A. SNOOK.
